(57) CLAIM

The ornamental design for a lighter holder, as shown and described.

DESCRIPTION

FIG. 1 is a perspective view showing my new design.

FIG. 2 is a front view thereof.

FIG. 3 is a rear view thereof.

FIG. 4 is a right end view thereof.

FIG. 5 is a left end view thereof.

FIG. 6 is a top view thereof.

FIG. 7 is a bottom view thereof; and,

FIG. 8 is a perspective view showing how a disposable lighter installed into the lighter holder, wherein no claim is claimed for the disposable lighter as shown, which is merely for illustrating purpose to show the overall appearance of the lighter holder of my new design mounted with the disposable lighter.
